[57] CLAIM

The ornamental design for a pipe shoe guide, as shown and described.

DESCRIPTION

FIG. 1 is a front perspective view of a pipe shoe guide, showing my new design;

FIG. 2 is a rear perspective view thereof;

FIG. 3 is a side elevation view thereof with the opposite side being a mirror image thereof; and,

FIG. 4 is a bottom plan view thereof.

The broken line showing of a pipe shoe, a beam, and another guide in FIG. 1 is for illustration purposes only and forms no part of the claimed design.

FIG. 1

FIG. 2

FIG. 3

FIG. 4
